DESIGN FOR A COMBINED HAT AND
COAT RACK

Gran-vill Thompson, Poplin, Mo.

Application October 26, 1946, Serial No. 134,291

Term of patent 14 years

(Cl. D33—8)

To all whom it may concern:

Be it known that I, Gran-vill Thompson, a citizen of the United States, residing at Joplin, in the county of Jasper and State of Missouri, have invented a new, original, and ornamental Design for a Combined Hat and Coat Rack, of which the following is a specification, reference being had to the accompanying drawing, forming part thereof.

In the drawing,

Figure 1 is a front elevation of a combined hat and coat rack showing my new design as it appears with the hat holding portion folded upwardly.

Figure 2 is a side elevation thereof.

Figure 3 is a side elevation thereof as it appears with the hat holding portion lowered into hat receiving position.

I claim:

The ornamental design for a combined hat and coat rack, as shown and described.

GRAN-VILL THOMPSON.
